UNITED STATES PATENT OFFICE.

CHARLES FRANCIS JENKINS, OF WASHINGTON, DISTRICT OF COLUMBIA.

VEHICLE-TIRE.

1,062,011.

Specification of Letters Patent.

Patented May 20, 1913.

Application filed June 27, 1912. Serial No. 706,188.

To all whom it may concern:

Be it known that I, CHARLES FRANCIS JENKINS, a citizen of the United States, residing at Washington, in the District of Columbia, have invented certain new and useful Improvements in Vehicle-Tires, of which the following is a specification, reference being had therein to the accompanying drawing.

10 This invention relates to tires for heavy vehicles and especially such as are made of wood, the general object being to avoid the usual results of expansion and contraction of the wood under varying weather conditions, 15 or change in the amount of moisture in the wood. The desired ends are reached by using an annular heavy spring within the wood or at some distance from its tread surface, in such manner that it is protected 20 from abrasion resulting from contact with the roadway.

In the accompanying drawings, showing the preferred embodiment of the invention, Figure 1 shows in side elevation a portion 25 of a tire embodying the invention. Fig. 2 is a cross sectional view of the same tire. Fig. 3 is a view similar to Fig. 2 showing the parts slightly separated as in the final step of assembling. Fig. 4 is a side view, 30 partly in section, showing the preferred manner of connecting the ends of the spring. Figs. 5 and 6 are cross sections of different forms of rods from which the spring coil is sometimes made.

35 In these figures, A represents the tire which is made up of wood blocks B, B' put together to form right and left rings extending around the wheel and constituting closely contiguous halves of the wood body.

40 The meeting faces of the rings are provided with annular registering grooves, B², at some distance from the tread surface, and in the tubular passage formed by the grooves, when the halves are thus put together, lies a very strong annular spring, 45 preferably a helical coil C formed from a round or a rectangular rod such as is indicated in Figs. 5 or 6. From one end of this coil projects a coil C' of slightly greater 50 diameter externally than the interior of the

main coil. This smaller coil is inserted in the open opposite end of the main coil, usually by forcibly imparting to the main coil a slight unwinding movement, entering the smaller coil therein and then releasing the 55 larger coil.

The two rings of wood are placed in angle irons D', D, respectively, the endless spring band is placed between the halves, and they are then drawn together by bolts D², when the tire is ready to be placed upon the wheel, where it is secured by devices not shown. The diameter of the coil is slightly less than the diameter of the channel in which it lies and the diameter of the spring 65 ring is slightly less than the diameter of the ring formed by the annular passage. The spring ring is placed between the halves of the tire body as shown in Fig. 3 and when the halves are drawn together by the bolts, 70 the spring being of circular cross section, is forcibly stretched and is under high tension when it reaches its place between the meeting wood rings; and if thereafter the wood expands, the spring yields slightly, 75 while if it shrinks the spring contracts, and thus the wood is always firmly held. In this form, the spring is fully protected upon all sides, although this is not indispensable, and in every embodiment of the invention 80 it is essential that the spring should lie at some distance within the tread surface so that it may not meet the surface of the roadway.

It may be noted that in all cases the tire 85 presents a large traction surface, the two halves, so far as this feature is concerned, being as effective as if the tire were undivided, and further that while I have shown the tire body as made up of but two rings I do not 90 wish to limit myself to a particular number, whether one or more.

What I claim is:

The combination of a tire body made up 95 of an annular series of wood blocks, divided in its own plane and having the meeting faces of the two rings of blocks provided with annular registering grooves forming an annular closed channel, a longitudinally extensible spring, adapted to lie in said chan- 100

nel, formed into a continuous ring having its internal diameter normally less than that of the annular channel, and means for forcing and binding together the two annular members of said body, to extend said spring and inclose it in said channel.

In testimony whereof I affix my signature in presence of two witnesses.

CHARLES FRANCIS JENKINS.
